UNITED STATES PATENT OFFICE.

ROBERT LEE WHITENER, OF CHARLOTTE, NORTH CAROLINA, ASSIGNOR OF ONE-HALF
TO SAMUEL SCHWARTZ, OF CHARLOTTE, NORTH CAROLINA.

MATCH-STAND.

1,269,768.

Specification of Letters Patent. Patented June 18, 1918.

Application filed January 2, 1918. Serial No. 210,111.

To all whom it may concern:

Be it known that I, ROBERT L. WHITENER, a citizen of the United States, and a resident of Charlotte, in the county of Mecklenburg and State of North Carolina, have invented certain new and useful Improvements in Match-Stands, of which the following is a specification.

My invention is an improvement in match stands, and has for its object to provide a device of the character specified wherein a holder is provided for matches of transparent material, so that the matches are visible through the holder, and wherein advertising matter may be arranged within the holder to be visible through the same, the holder being closed at its top and having a change compartment at the top and at its bottom a hopper through which is slidable a plunger having grooves for receiving individual matches to remove them from the holder, the hopper being held in place by the plunger which is removable to permit the removal of the hopper to permit the insertion of matches.

In the drawings:

Figure 1 is a perspective view of the improved holder;

Fig. 2 is a vertical section;

Fig. 3 is a similar section at right angles to Fig. 2;

Fig. 4 is a perspective view of the plunger with one of the heads removed;

Fig. 5 is a partial longitudinal section of one end of the plunger.

In the present embodiment of the invention, a holder is provided, consisting of a casing 1 of glass or other suitable material open at its bottom, and closed at its top, and supported by a suitable base 2 which is integral therewith, the said base being ornamental and hollow, as shown, so that the interior of the holder may be communicated with through the base.

The closure 3 at the top of the holder is integral with the casing, and is in the form of a change tray, having its deepest portion at the front of the holder. The body or casing 1 of the holder is integral with the base, as shown more particularly in Figs. 2 and 3, and the said body is of the same cross section throughout, and the matches are introduced through the open bottom of the holder.

The holder has circular openings 4 in its

end walls, the said openings being in register, and being adapted to receive a plunger 5, which is in the form of an approximately cylindrical bar, having heads 6 forming handles for operating the plunger. One of these heads or handles is made detachable, as shown more particularly in Fig. 5. The end of the plunger 5 at the said handle is split, as indicated at 5^a, and the head has a ferrule which fits over the split end. There is sufficient resiliency to hold the handle in place.

A hopper 7 is arranged within the holder, and the said hopper has a substantially cylindrical portion 8 at its bottom, through which the plunger 5 is slideable, the said cylindrical portion being adapted to register with the openings 4 to permit the passage of the plunger, and the hopper is retained in place by the plunger. Bearings 4^a are arranged in the openings 4 for the plunger 5, each bearing having a flange at its outer end for engaging the end wall of the holder. The hopper is of a length corresponding approximately to that of the body of the holder, and of a width at its widest parts such that the side walls thereof will engage with the side walls of the holder, and the matches in the holder are thus deflected down upon the upper surface of the plunger. At one end the plunger has oppositely arranged longitudinally extending grooves 9, each of a depth and a length to receive a match 10, and it will be evident that when these grooves are in register with the communication between the body of the hopper and the cylindrical portion a match will find its way into the groove so that when the plunger is withdrawn and turned to bring the groove beneath the plunger the match will fall out, as indicated in Fig. 1. The plunger is also provided with longitudinally extending grooves 11, insufficient in depth to receive a match, and the said grooves act to straighten the matches in the lower portion of the hopper, so that they will be parallel with the grooves 9.

In use, any desired form of advertisement may be arranged within the body 1 of the holder, and the said advertisement will be protected from injury, while at the same time it is visible through the glass. But a single match may be withdrawn at one operation, and the device thus acts to save the matches. It will be noticed from an inspection of Fig. 2 that at the ends of the cylin-

drical portion 8 of the hopper outwardly extending flanges 12 are provided, which engage the ends of the body of the holder to properly hold the hopper in place.

5 I claim:

1. A device of the character specified, comprising a holder of transparent material consisting of a body substantially rectangular in cross section and closed at its top and 10 open at its bottom and having a hollow base, at the bottom, said body of the holder having in its end walls registering circular openings, a hopper having a cylindrical portion at its bottom adapted to register with 15 the openings, a plunger movable through the openings and through the cylindrical portion of the hopper, said plunger having oppositely arranged grooves at one end for receiving a match to remove the same from 20 the holder, the ends of the plunger having a head detachably connected therewith for permitting the removal of the plunger when the head is detached to permit the removal of the hopper, said hopper being held in 25 place in the holder by the plunger.

2. A device of the character specified, comprising a holder of transparent material consisting of a body substantially rectangular in cross section and closed at its top and open at its bottom and having a hollow base at the bottom, said body of the holder having in its end walls registering circular openings, a hopper having a cylindrical portion at its bottom adapted to register with 30 35

the openings, and a plunger movable through the openings and through the cylindrical portion of the hopper, said plunger having oppositely arranged grooves at one end for receiving a match to remove the same from 40 the holder.

3. A device of the character specified, comprising a holder of transparent material consisting of a body substantially rectangular in cross section and closed at its top and open at its bottom and having a hollow base 45 at the bottom, said body of the holder having in its end walls registering circular openings, a hopper having a cylindrical portion at its bottom adapted to register with the openings, and a plunger movable 50 through the openings and through the cylindrical portion of the hopper, said plunger having oppositely arranged grooves at one end for receiving a match to remove the same from the holder, and having longitudinally extending grooves of lesser depth 55 for straightening the matches.

4. A device of the character specified, comprising a holder closed at its top and open at its bottom, a hopper having a cylindrical portion adapted to fit within the bottom to close the same, said holder having openings at the ends of the cylindrical portion for receiving a plunger to hold the hopper in place, the plunger having grooves for receiving individual matches.

ROBERT LEE WHITENER.
